UNITED STATES PATENT OFFICE.

BENJAMIN JOSEPH JOHN GOULDING, OF ALTRINCHAM, CHESTER, ENGLAND, AS
SIGNOR TO LINOTYPE AND MACHINERY LIMITED, OF LONDON, ENGLAND, A BRIT-
ISH COMPANY.

TYPOGRAPHICAL LINE-CASTING MACHINE.

Application filed April 21, 1922. Serial No. 555,833.

To all whom it may concern:

Be it known that I, BENJAMIN JOSEPH JOHN GOULDING, a subject of the King of the United Kingdom of Great Britain and Ireland, and residing at Linotype and Machinery Works, Altrincham, in the county of Chester, England, have invented new and useful Improvements in Typographical Line-Casting Machines, of which the following is a specification.

This invention relates to typographical line-casting machines such as those known commercially under the trade mark "Linotype" and kindred machines, and it has for its object to ensure the manufacture of slugs which shall be better suited for the production of stereotypes by the so-called "dry flong" method, than have been those heretofore produced by similar means.

The production of the just-mentioned dry flongs, as now practised in many newspaper offices, subjects the slugs to very heavy pressures, and if the slugs be defective or spongy in the immediate vicinity of their printing edges as by the existence at those parts of blow holes, these pressures have a tendency to depress the said parts below height-to-paper and may result in the production of corresponding depressions in the stereotypes cast from the flongs, and corresponding white or weak patches in the prints obtained from such stereotypes.

As is already well known, the before-mentioned slugs are cast in a mold, to the front of which is presented a line of matrices assembled in order of composition, the molten type metal being forced into the rear of the mold through a throat leading from a pump which intermittently supplies the metal at the desired pressure.

The throat is moved into and out of contact with the mold, and during the non-delivering operations of the pump, the upper part of such throat is occupied by air which mostly escapes through shallow grooves usually formed for the purpose in the front face of the metal-pot mouth-piece, during the metal-delivering operation of said pump.

It occasionally, however, does happen that some of this air becomes trapped in the mold when the metal is injected there-

into, with the result that blow holes are formed in the slugs.

The invention will now be described by reference to the accompanying drawing which is a vertical section of as much of a machine of the type before particularized as is necessary to give a clear understanding of such invention.

According to this invention the before-mentioned improved result is obtained by providing a small air chamber 1, on, or as represented, preferably cast in, the upper part of the metal delivery throat 2, which latter, in other respects, is of the ordinary well-known construction connecting at its lower end with the pump cylinder 3 and being provided at its upper end with the usual perforated mouth-piece 4. The usual heating devices (not shown) guard against solidification of the metal in the pot throat and mouth-piece.

The mouth-piece 4, as ordinarily, is moved into and out of metal-tight contact with the back of the mold 5, carried by the mold wheel 6, and this mold, in turn, makes close contact with the back of the assembled line of matrices 7 which is then held in casting position in the so-called first elevator 8.

In the employment of a metal-delivery throat of the construction illustrated, it is found that some of the air in said throat becomes trapped and compressed in the chamber 1 during the metal-ejecting action of the pump, so that during the non-ejecting action of said pump and the cooling and consequent shrinking of the slug in the mold, that air in expanding, exercises a more or less uniform pressure on the rapidly solidifying slug. By these means it is found that the resultant slugs are of more uniform

texture throughout their substance, than are those as ordinarily constructed, and that, if blow-holes do occur in them, these holes are generally located sufficiently far from the character-bearing edge, as to present no danger of that edge collapsing under the pressures to which the slugs will ordinarily be exposed.

It has been found that the best results are obtained when the air chamber 1, is, as shown in the drawing, of approximately ovoid shape in transverse section, with the

smaller end nearer to or directed towards the mouth-piece 4, it being assumed that this particular form provides a freer access for the air into and out of the said chamber.

5 Having described my invention, I declare that what I claim and desire to secure by Letters Patent is:—

1. In a typographical line-casting machine, the combination of an air-vented mold, 10 a pump for injecting molten metal into the mold, and a metal-delivery throat having a passage leading from the pump to the mold, the said throat being formed with an air chamber in open communication only with 15 the passage through the throat, whereby the air compressed within said chamber during the pumping operation will exert pressure upon the rapidly solidifying metal within the mold when the pump pressure is relieved.
- 20 2. In a typographical line-casting machine, the combination of an air-vented mold, a pump for injecting molten metal into the mold, and a metal-delivery throat

having a passage leading from the pump to the mold and provided with a mouth-piece 25 at its delivery end, the said throat being formed adjacent the mouth-piece with an air chamber in open communication only with the passage through the throat, whereby the air compressed within said chamber during 30 the pumping operation will exert pressure upon the rapidly solidifying metal within the mold when the pump pressure is relieved.

3. In a typographical line-casting machine, the combination with a metal-delivery throat of an air chamber in open connection only with the passage through said 35 throat, the said air chamber being of approximately ovoid shape in transverse section with the smaller end directed towards the delivery or outlet end of the throat.

In testimony whereof I have affixed my signature hereto.

BENJAMIN JOSEPH JOHN GOULDING.
